CLAIM

We claim the ornamental design for a masher, as shown and described.

DESCRIPTION

FIG. 1 is a perspective view of a masher according to the new design;

FIG. 2 is a top view of the masher shown in FIG. 1;

FIG. 3 is a bottom view of the masher shown in FIG. 1;

FIG. 4 is a front view of the masher shown in FIG. 1; and,

FIG. 5 is a right side view of the masher shown in FIG. 1, the left side view of the masher being a mirror image thereof.
